UNITED STATES PATENT OFFICE.

ROY W. ADAMS, OF NEW BRITAIN, CONNECTICUT.

FIGUREHEAD.

Application filed October 16, 1922. Serial No. 594,958.

To all whom it may concern:

Be it known that I, Roy W. Adams, citizen of the United States, residing in the city of New Britain, county of Hartford, 5 and State of Connecticut, have invented a new Figurehead, of which the following is a full and complete description.

The object of my invention is to provide a novel figurehead in the form of a winged 10 creature which will move its wings in imitation of flight, when acted upon by a current of air.

In the accompanying drawings:

Figure I shows a figurehead representing 15 a winged creature mounted on the radiator cap of an automobile.

Figure II is a plan view of the mechanism which causes the wings of Figure I to move up and down.

20 Figure III is a sectional view of Figure II on the line A—A.

Figures IV, V, VI, and VII are a series 25 of side elevations showing different positions and relations of the moving parts throughout a complete cycle.

The same number is used to designate the same part in all the figures.

In the different figures; 1 is a metal plate; 30 3 and 3' are rectangular grooves, one in each side of plate 1; 4 and 4' are plates with projections 5 and 5' engaging grooves 3 and 3' respectively; 6 is a round bar extending through slot 2 in plate 1, connecting plates 4 and 4'. The members 4, 4', and 6 form a 35 unit which is free to slide up and down on plate 1, providing the projections 5 and 5' follow the grooves 3 and 3'. 8 and 8' are the wings supported of the bars 14 and 14' which are connected to the bar 6 by a hinge 40 joint at 9 and 9' and fulcrumed through the holes 7 and 7' in the body 12. 10 and 11 are two sets of springs connected to the lower ends of the plates 4 and 4', and to anchor pins in plate 1.

45 Considering forward to mean opposite to the direction indicated by the arrows *a*, and backward to mean in the direction indicated by arrows *a*, then springs 10 are so positioned as to tend to cause a forward and downward movement of the lower ends of members 4 and 4', and the springs 11 are so positioned as to tend to cause a backward and upward movement of the lower ends of members 4 and 4'.

50 55 In the series of Figures IV, V, VI, and VII the lines *b* represent the inclination of the

wing surfaces. The arrows *a* indicate the direction of a current of air, such as wind or the impact of air upon a moving body. In Figure IV, a current of air moving in 60 the direction indicated by the arrow *a*, acting upon a surface inclined so as to receive the impact of said current of air on its upper surface, its forward edge being lower than its rear edge as shown by the line *b*, 65 would cause the surface to move in a downward direction. Since the bars 14 and 14', which support the wings, are fulcrumed at 7 and 7', as shown at Figure III, a downward motion of the wings 8 and 8' will cause 70 an upward motion of the sliding unit composed of the parts 4, 4', and 6. When this part of the cycle has been completed the parts will have changed from the position shown in Figure IV to the position shown 75 in Figure V. At the position shown in Figure V the springs of the set 10 are under tension while the springs of the set 11 are released from tension by nature of their respective positions. Therefore, as soon as 80 the parts reach the position shown in Figure V, they are pulled into the position shown in Figure VI by the springs of the set 10. This will have changed the angle of inclination of the parts 4, 4', and 6, and since the 85 joints 9 and 9' are hinge joints and allow motion in a vertical direction only, any change of the inclination of the parts 4, 4', and 6 will cause a corresponding change or reversal in the direction of inclination of 90 the wing surfaces 8 and 8' as indicated by the line *B*, Figure VI. A current of air moving in the direction indicated by the arrow *a*, Figure VI, would cause a wing surface, inclined as line *b*, to move upward 95 with a corresponding downward movement of the parts 4, 4', and 6 to the position shown in Figure VII. Now the springs of set 10 are released from tension while the springs of set 11 are brought under tension. 100 The parts will then be pulled into the position shown in Figure IV by the springs of set 11. This completes the cycle and the action will continue as long as a current of air strong enough to work the mechanism 105 is supplied.

I do not, however, wish to confine or limit myself to the particular arrangement of members as shown or described herein as a greater or lesser number of some of the 110 members could be used, and various different positionings of some of the members, par-

ticularly the springs, could be used without departure from the spirit of my invention.

I claim:

A representation of a winged figure having a hollow body, movable wings and support members therefore extending within said body, a fixed plate having a slot and a closed guide groove on either side of said

plate, a bar in said slot having its ends operatively connected to said support members, cranks connected to said bar, each crank having a pin slidable in one of said grooves, springs fixed to said plate and said cranks each said spring operative to actuate one of said pins along its groove.

ROY W. ADAMS.
